(57) **CLAIM**

The ornamental design for a “remote control for television,” as shown and described.

DESCRIPTION

FIG. 1 is a perspective view of remote control for television showing our new design;

FIG. 2 is another perspective view of remote control for television showing our new design;

FIG. 3 is a front view thereof;

FIG. 4 is a rear view thereof;

FIG. 5 is a left side elevational view thereof;

FIG. 6 is a right side elevational view thereof;

FIG. 7 is a top view thereof; and,

FIG. 8 is a bottom view thereof.

The broken lines in the figures depict portions of the remote control for television that form no part of the claimed design.
